[57] CLAIM

The ornamental design for a stay for holding a gas pump nozzle trigger in the open position, as shown.

DESCRIPTION

FIG. 1 is a perspective view of a stay for holding a gas pump nozzle trigger in the open position showing my new design;

FIG. 2 is a front elevation view thereof, the rear being a mirror image;

FIG. 3 is a top plan view thereof;

FIG. 4 is a bottom plan view thereof; and

FIG. 5 is an end elevational view thereof, the opposite end being a mirror image thereof.
